(57) **CLAIM**

The ornamental design for a motorcycle fairing vent cover, as shown and described.

DESCRIPTION

FIG. 1 is a perspective left side view of a motorcycle fairing vent cover embodying our new design, the dotted line representations of a portion of a left side of a motorcycle fairing form no part of the claimed design;

FIG. 2 is a top plan view;

FIG. 3 is a left outer side view thereof;

FIG. 4 is a front elevational view thereof;

FIG. 5 is a rear elevational view thereof;

FIG. 6 is a right inner side view thereof; and,

FIG. 7 is a bottom plan view thereof.
